US00D562568S

(12) **United States Design Patent** (10) **Patent No.:** **US D562,568 S**
Johnston et al. (45) **Date of Patent:** **** Feb. 26, 2008**

(54) **TWO-DIMENSIONAL SHEET MATERIAL**

(76) Inventors: **Nik L. Johnston**, 6050 W. Mansfield, #4, Denver, CO (US) 80235; **John P. Bardeen**, 201 S. Franklin St., Denver, CO (US) 80209

(**) Term: **14 Years**

(21) Appl. No.: **29/211,612**

(22) Filed: **Aug. 17, 2004**

(51) **LOC (8) Cl.** **05-06**

(52) **U.S. Cl.** **D5/60**

(58) **Field of Classification Search** ..... D5/1-3, D5/5, 7-8, 11, 13-16, 19-20, 23-28, 30, D5/32, 35-37, 39, 43, 45, 47, 49-50, 52-66, D5/99; D2/479, 994; D6/582-583, 595-596, D6/598, 608, 603-606, 613, 616, 617, 619, D6/622; 428/17-18, 151, 154, 156, 171, 428/187, 198, 199, 540, 542.2, 542.6, 919, 428/904.4; D24/124, 128; D25/142, 152; D21/605; 5/413 AM, 709; 162/134, 140, 162/231; 156/148, 209; D7/396.4-5

See application file for complete search history.
